UNITED STATES PATENT OFFICE.

WILLIAM D. JANES, OF SAGINAW, MICHIGAN, ASSIGNOR TO THE QUAKER SHADE ROLLER COMPANY, OF BAY CITY, MICHIGAN.

DEVICE FOR ATTACHING WINDOW-SHADES TO ROLLERS.

SPECIFICATION forming part of Letters Patent No. 766,257, dated August 2, 1904.

Application filed March 19, 1904. Serial No. 198,953. (No model.)

To all whom it may concern:

Be it known that I, WILLIAM D. JANES, a citizen of the United States, residing at Saginaw, in the county of Saginaw and State of Michigan, have invented certain new and useful Improvements in Devices for Attaching Window-Shades to Rollers; and I do hereby declare the following to be a full, clear, and exact description of the invention, such as will enable others skilled in the art to which it appertains to make and use the same.

This invention is a device for attaching window-shades to rollers, and relates more particularly to that class of such devices in which the roller is longitudinally grooved and the end of the shade is fixed in the groove by means of small bowed plates of sheet metal having teeth or prongs formed on their longitudinal edges engaging the walls of the groove to fasten the shade in the groove by spreading out and embedding in its walls when the bowed plate is flattened or its curvature reduced by driving. It will be noted that this class of fastening operates by flattening the bowed plate, thus spreading its longitudinal edges and forcing the teeth downwardly and outwardly in opposite directions. In flattening the plate it is of course necessary to bend the metal. During the flattening of the plate while the teeth are entering the opposite walls of the groove the resistance of the two walls must be substantially equal, else the teeth will not enter the opposite walls equally.

It is found in practice that unless considerable care is taken to accurately adjust the prongs of the grooved plate relatively to the groove of the roller and unless the driving force is applied directly above the center of the plate the prongs on one side will go deeper into the walls of the groove than those on the other side, often resulting in failure to grip on one side and reducing or destroying the holding power of the plate. If driven over on the shade side too far, the full width of the plate cuts through the shade, and the shade is apt to tear out at that point. Also if driven over too far to one side the prongs go clear through into the bore of the roller and interfere with the action of the spring. To over-

come these defects, make the plate more easily applied to the roller, and to increase its holding power, I have devised the improved fastening shown in the accompanying drawings, forming a part of this specification.

Figure 1 is a side view of a grooved roller with the shade in place, one end of the shade being turned back to show the groove and my fastening device applied ready for driving. Fig. 2 is an end view of the same. Fig. 3 is an end view showing the fastening device pressed in place ready to be flattened by driving. Fig. 4 is a side view of a shade fastened to its roller. Fig. 5 is an end view of the parts shown in Fig. 4. Fig. 6 is an enlarged perspective of the fastening device ready to be driven. Fig. 7 is a similar view showing the device forced into place. Fig. 8 is a perspective of a modified form of my improvement.

In the drawings, R represents the roller, provided with the groove G, to which the shade is attached by means of my improved fastening device, which consists, as above described, in the usual bowed plate 1, having outwardly-extending teeth or prongs 2 2', adapted to enter the walls of the groove G when the plate 1 is flattened, as shown in Figs. 5 and 7.

The main object of this invention is to insure that the oppositely-disposed prongs 2 2' shall enter the walls equally. This is accomplished by providing the bowed plate 1 near its middle with one or more downwardly-extending prongs 3, adapted to drive straight into the face of the groove G, and thus guide the middle part of the plate 1 straight down to the middle of the groove G, so that the opposing prongs 2 2' as they straighten out under the driving force will enter equally the opposite walls of the groove G instead of entering them unequally, as was frequently the case before the prongs 3 were used.

The prongs 3 may be fixed to the concave side of the plate 1 in any suitable manner; but when the prongs 3 are formed as shown in the drawings by slitting the plate 1 and bending the prongs 3 down, as shown in Figs. 6 and 8, an additional advantage is attained.

This is evident when it is remembered that the prongs 2 2' are forced outwardly by the act of straightening or flattening the plate 1. The greatest bending occurs in the middle of the plate, and if the plate is made of sheet metal having considerable elasticity it has a tendency to bow up or loosen after being driven and also by its resistance to straightening while being driven tends to tear the wood and make holes in the walls of the groove G larger than the prongs 2 2', thus reducing its grip on the roller.

By forming the prongs 3 from the body of the plate 1, as shown in Figs. 6 and 8, the cross-section of middle portion of the plate is reduced, permitting the plate 1 to flatten easier while being driven and allowing the prongs 2 2' to follow their natural tendency to enter straight into the walls of the groove, thus making holes in the roller of the same size as the prongs and greatly increasing their holding power. The reduced weakened cross-section of the plate 1 can exert less tendency to bow up after being driven, and the prong 3 furthermore operates as a nail or spike to check any remaining tendency to withdraw. It is thus seen that the prong 3 guides the plate 1 positively into place, so that the prongs 2 2' are always driven equally into the walls of the groove, and, furthermore, that forming the prongs from the body of the plate operates to increase the holding power of the plate.

In Figs. 1, 4, 6, and 7 I have illustrated a plate formed with two prongs, one at each side, and in Fig. 8 a central prong punched from the middle of the plate. It is obvious that the form, number, and location of these

prongs may be varied to some extent without departing from the spirit of my invention, which resides, essentially, in the guiding-prong adapted to direct the body of the plate fair down upon the groove, while the prongs 2 2' spread out in opposite directions and enter the walls of the groove under the bending action of the plate 1 as it flattens while being forced down upon the shade.

What I claim as my invention, and desire to secure by Letters Patent, is as follows:

1. In combination with a bowed plate having opposite edges provided with outwardly-projecting teeth adapted to enter the opposite walls of a longitudinal groove in a shade-roller when the plate is flattened; means for guiding the middle portion of the plate during the flattening action, comprising an inwardly-projecting prong fixed to the under side of said bowed plate, for the purposes set forth.

2. In combination with a bowed plate having opposite edges provided with outwardly-projecting teeth adapted to enter the opposite walls of a longitudinal groove in a shade-roller when the plate is flattened; means for guiding the middle portion of the plate during the flattening action, comprising an inwardly-projecting member formed by slitting the plate to form a prong and bending in the prong so formed.

In testimony whereof I affix my signature in presence of two witnesses.

WILLIAM D. JANES.
